The ornamental design for an all-in-one computer, as shown and described.

DESCRIPTION

FIG. 1 is a front perspective view of an all-in-one computer showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a back perspective view thereof.

The broken lines immediately adjacent to the claim represent the bounds of the claimed design while all other broken lines are directed to environment; the broken lines form no part of the claimed design.
